UNITED STATES PATENT OFFICE.

ALFRED F. MASURY, OF NEW YORK, N. Y., ASSIGNOR TO INTERNATIONAL MOTOR COMPANY, OF NEW YORK, N. Y., A CORPORATION OF DELAWARE.

SEAT.

Application filed September 27, 1926. Serial No. 137,921.

The present invention relates generally to swivel seats of the type described in the application of William E. Hasselkus, Serial No. 113,649, filed June 4, 1926.

5 An object of the present invention is to provide a swivel seat which may be turned to face in a plurality of directions and to enable the seat to be secured in any of such positions to prevent it from turning. Where 10 seats of this character are used upon trains, busses, etc., it is frequently necessary to reverse the direction in which certain, or all of the seats face. In such event, it is desirable that the seats be equipped with 15 means which enable this to be accomplished with little effort and loss of time. The present invention supplies an operating mechanism of this character.

Reference will now be had to the accompanying drawings forming a part hereof 20 wherein:

Figure 1 is an elevation, partly in section, of the invention.

Figure 2 is an elevation, partly in section, 25 of a slightly modified form wherein a plurality of seats are operated simultaneously from a common operating means.

Figure 3 is an elevation showing a plurality of seats operated by the common 30 means shown in Figure 3.

In the drawings, a represents a base or pedestal, having a vertical cylindrical housing a' which receives a bearing a^2 having a flange a^3 . The seat frame b is provided 35 with a downwardly extending shaft b' which is received in the bearing a^2 and a flange b^2 on the shaft b' rests on the flange a^3 .

At a plurality of points in the flange b^2 40 are provided notches b^3 and a notch a^4 is provided in the flange a^3 . A roller detent c normally engages a notch a^4 and a notch b^3 which happens to be positioned above a^4 ,

thus preventing the frame b from rotating. The base a is provided with a pivot c' 45 which mounts a lever arm c^2 having arms c^3 and c^4 . A spring d serves to engage the detent normally. In Figure 1, the arm c^2 has a pedal extension e which lies under the floor and has a foot pedal e' . This pedal 50 is situated at a convenient place and, when it is desired to reverse the seat, the pedal is depressed and the seat rotated.

In Figures 2 and 3 the seats are operated simultaneously by means of the following 55 mechanism. Shaft f is mounted under the floor boards and has keyed thereto a lever g provided with a pedal g' . At each seat an arm h is keyed to the shaft f and a link i connects h with the short arm j on 60 arm c^2 . It will be apparent that upon depressing the pedal g' all of the seats may be released simultaneously.

While the above serves to illustrate the preferred forms of the invention, it is not to 65 be understood to be limited, save as defined in the appended claim.

What I claim is:

In combination, a plurality of independently rotatable seats, bases therefor, means 70 to permit rotation of the seats in the bases, separate means to prevent rotation, means to release the last named means and simultaneously render the first means effective, a shaft mounted under the floor upon which 75 the bases are mounted, connections between the shaft and releasing means, an operating lever secured to the shaft and mounted under the floor, and means for actuating the lever adjacent a seat but apart from the base 80 structure to operate the releasing means whereby the actuating means may be operated and a seat turned by the operator.

This specification signed this 23rd day of September A. D. 1926.

ALFRED F. MASURY.
